US0D1017076S

(12) **United States Design Patent** (10) **Patent No.:** **US D1,017,076 S**
(45) **Date of Patent:** **** Mar. 5, 2024**

(54) **GATE WITH DISPLAYS**

(71) Applicant: **LG DISPLAY CO., LTD.**, Seoul (KR)

(72) Inventors: **Seokjin Im**, Paju-si (KR); **Jeongeon Seong**, Paju-si (KR); **Seokhyo Cho**, Paju-si (KR); **Hyunjung Song**, Paju-si (KR); **Soonmin Kwon**, Paju-si (KR); **Kihyoung Kim**, Paju-si (KR)

(73) Assignee: **LG DISPLAY CO., LTD.**, Seoul (KR)

(**) Term: **15 Years**

(21) Appl. No.: **29/823,024**

(22) Filed: **Jan. 13, 2022**

(30) **Foreign Application Priority Data**

Jul. 21, 2021 (KR) 30-2021-0034685

(51) **LOC (14) Cl.** **25-02**

(52) **U.S. Cl.**

USPC **D25/56**; D25/18
